(57) **CLAIM**

The ornamental design for a “computer”, as shown and described.

DESCRIPTION

FIG. 1 is a bottom, front, right, perspective view of a computer;

FIG. 2 is a bottom, front, right, perspective view thereof in a first alternate configuration of use; and,

FIG. 3 is a bottom, right, front perspective view thereof in a second alternate configuration of use.

The even dashed broken lines in the drawings represent portions of the computer that form no part of the claimed design. The dot-dash broken lines represent boundaries that separate the unclaimed center portion of the screen from the rest of the computer. The keyboard shown in even dash broken lines in FIGS. 1-2 represents environment. None of the broken lines form part of the claimed design.
